UNITED STATES PATENT OFFICE.

ALVIN L. BRUMBACH, OF READING, PENNSYLVANIA, ASSIGNOR TO TEXTILE MACHINE WORKS, OF WYOMISSING, PENNSYLVANIA, A CORPORATION OF PENNSYLVANIA.

SLOTTING-MACHINE ATTACHMENT.

Application filed August 30, 1924. Serial No. 735,142.

My invention relates to slotting machines; and my main object is to provide for satisfactorily cutting a succession of closely spaced slots which have only thin walls of material between them.

A particular work in mind is the slotting of needle-bar or narrowing bar blanks for the reception of the needle shanks of full-fashioned knitting machines; in which case the close spacing of the needles necessitates very thin and correspondingly weakened partition walls, while at the same time calling for the greatest possible accuracy and uniformity in the needle-receiving slots. It has been found in practice that the fact that the slot-cutting tool is in each successive cutting movement flanked on one side by a wall of solid metal and on the other by only a thin wall of metal separating it from the previously cut slot, is apt to cause undue lateral strain on each newly formed wall with resulting breakage or imperfection.

To overcome this trouble I provide for automatically supporting the thin wall formed in cutting each successive slot; and for thereafter withdrawing such support to permit of the required step movement for the succeeding cut; as fully set forth in connection with the accompanying drawings and clearly defined in the claims.

Fig. 1 is a plan view of my attachment as preferably applied; shown in connection with a merely diagrammatic indication of the rotary-cutter and work-holder elements ordinarily employed in slotting machines. A needle-bar blank is also indicated in position upon the latter, by dash-and-dot lines.

Fig. 2 is a corresponding elevation indicating, partly in cross-section, the relative positions of the known machine parts.

Figs. 3 and 4 are enlarged detail views of the slot-engaging portion of the bracing finger.

The well known essential parts of a slotting machine are only sufficiently indicated to show the relation thereto of my invention; the frame A of such a machine being crudely indicated in dotted lines, with an integral bracket A' to which a supporting frame 10 for my slot-wall bracing-finger is shown rigidly secured as the simplest means of attachment. A fragment only of a work holder table B is indicated, with a portion of a bar blank C indicated thereon as being operated upon by the transversely movable

rotary cutter D; the section of said work holder shown in Fig. 2 indicating an ordinary feed screw C' by which step-by-step movements are imparted thereto in the direction of the arrow as determined by the spacing of the series of the slots to be cut by successive transverse movements of the cutter D; and the latter being operatively mounted on a carriage E suitably guided upon the frame A.

It will be understood that the essential slotting machine features thus indicated provide for effecting stepped slot-cutting movements of the cutter D cross-wise of the blank C. My invention consists merely in providing an automatically operated slot-wall bracing-finger whereby a newly formed tooth or slot-wall will be supported against the incidental lateral strain of the cutter so as to avoid possible breaking-down of a slender wall, and insure perfection in the work.

My slot-wall bracing-finger, as shown, consists of a slot-engaging member 11 the down-turned tip 12 of which is adapted to enter into a cut slot and extend along the length of the latter in contact with the solid metal flanking it; this member having a shank portion 13 which is adjustably secured to the body portion 14 of the finger by means of an adjusting screw 15 and set screw 16 as indicated. This body portion 14, as shown, has a pivot end by means of which it is swingingly mounted upon the frame bracket 10 on a pivot pin 20 having an operating arm 21; the movement of the finger being controlled by a cam device 22 fixed to the cutter carriage E.

The automatic operation of my slot-wall bracing-finger applied as above set forth, is as follows: The finger tip 12 is accurately set to space it from the path of the cutter D a distance equal to the spacing of the slots being successively cut in the blank C by the transverse reciprocations of said cutter. After the first slot has been cut, the withdrawing movement of the cutter carriage E brings the high surface 22' of its fixed cam device 22 under the pivot-pin arm 21, and raises and maintains the finger tip 12 above the blank C on work holder B so as to permit the stepping forward movement required preliminary to the next slot-cutting movement. Before the cutter begins to cut the next slot however, the cam 22 permits the finger tip 12 to drop into the last

cut slot, thus providing a positive support or brace for the slender tooth or wall formed by the new cut; and this action is automatically repeated for each cutting 5 operation so that required perfectness of the slots and walls will be practically insured.

It will be readily understood that the particular construction and manner of application specifically set forth may be modified 10 without departing from the invention as defined in the claims.

What I claim is:

1. In combination with a slotting machine comprising a supporting frame and a 15 work holder and rotary-cutter carrier relatively movable thereon to effect stepped cutting movements transversely of the work holder; a movably mounted slot-wall bracing-finger mounted on the frame rearwardly 20 of the cutter path, and means for automatically moving said bracing-finger into a previously cut slot preliminary to each succeeding slot-cutting movement and withdrawing the same preliminary to each step 25 movement.

2. In combination with a slotting machine comprising a supporting frame, a work holder having a longitudinally step-

by-step movement, and a rotary-cutter carrier having a reciprocating transverse movement during each rest period of the work-holder; a slot-wall bracing-finger mounted on the frame rearward of the cutter path and movable toward and away from the work holder, and means for automatically 30 moving said bracing finger into a previously cut slot preliminary to each succeeding slot-cutting movement of the cutter and away therefrom preliminary to each step movement of the work holder. 40

3. A slotting machine comprising a supporting frame, a work-holder having a longitudinal step-by-step movement, a rotary-cutter carrier having a reciprocating transverse movement during each rest 45 period of the work-holder, a slot-wall bracing-finger mounted on said frame rearward of the cutter path to move toward and away from the work holder, and a finger-operating device fixed to said cutter carrier 50 and adapted to reversely position said finger during the rest and moving periods of the work holder.

In testimony whereof I affix my signature.

ALVIN L. BRUMBACH.
